UNITED STATES PATENT OFFICE

WILLIAM H. APPLEMAN, OF OLEAN, NEW YORK.

DEVICE FOR STEERING VEHICLES.

1,243,379.

Specification of Letters Patent. Patented Oct. 16, 1917.

Application filed October 15, 1914. Serial No. 866,863.

To all whom it may concern:

Be it known that I, WILLIAM H. APPLEMAN, a citizen of the United States, residing at Olean, N. Y., in the county of Cattaraugus, in the State of New York, have invented a new and useful Device for Steering Vehicles, of which the following is a specification.

My invention relates to improved methods 10 for imparting motion to what is known as the steering arm of steering devices.

The objects of my invention are to provide means for eliminating lost motion in case of wear, reduce the cost of construction, and 15 render the internal parts of the device far more accessible than those in devices now in use for a similar purpose.

I attain the objects of my invention by the mechanism illustrated in the accompanying 20 drawing in which, Figure 1 is a side elevation view partly in section with portions removed in order to afford a more complete view of the interior arrangement. Fig. 2 is a view chiefly in section taken through my 25 device at A. A. Fig. 3 is a plan view of a portion of the rocking member of my device. Fig. 4 is a front elevation view, and Fig. 5 a rear elevation view of my device as it would appear when observed at a right angle 30 from the steering post. Fig. 6 is a longitudinal view partly in section showing a slight modification of Fig. 2. Fig. 7 is an internal plan view of the outer plate of said 35 modification, and indicates that the opening through it is squared part way through said plate. Like numbers indicate like parts throughout the various figures.

A casing or housing 1 is provided for receiving and supporting the various members of my device in their proper relations, 40 said housing being formed in a single piece and containing a circular longitudinal and also a circular transverse chamber, both of which are machined throughout, the latter 45 having a lateral external opening on each side equal to the diameter of said transverse chamber. The bore of said longitudinal chamber is reduced at the lower end and forms an abutment for purposes hereinafter 50 mentioned, and the upper end is threaded and provided with small bosses on one side which have a slotted longitudinal opening through them as well as through the casing 55 wall to permit of contracting the top of said longitudinal chamber, similar bosses having a slotted opening through them and also

through the wall of the transverse chamber permits of the transverse chamber also being contracted when found desirable, said contractions being effected by compression bolts 60

1^a and 1^b respectively. An externally threaded adjustable sleeve 2 is inserted in the upper end of the longitudinal chamber which co-acting with the sleeve type abutment at the lower end of the longitudinal 65 chamber provides longitudinal as well as primary lateral bearing supports for a rotatable tubular steering post 3, the sleeve portion of which is pivotally confined within said bearings, and the longitudinal chamber 70 of housing 1. A worm 4 either integral with or rotatably secured to said steering post 3, encircles said post within said longitudinal chamber, said worm being directly sustained laterally by means of special end 75 thrust wearing rings 5 and 6, one of which is inserted at each end of the worm and thereby contacts with its respective abutment. A multiple piece rocker consisting primarily of a shaft 7 and circular flanged 80 plates 8 and 9 is inserted in said transverse chamber, said plates are machined on their inner, as well as peripheral faces, and by contacting peripherally journal fashion as well as laterally with the walls of said transverse 85 chamber constitute a most substantial pivotal support for all members of said rocker already or hereinafter specified. Plate 8 is rigidly secured to shaft 7 or may be integral therewith while plate 9 is rotatable as well 90 as laterally adjustable on said shaft. Located between said plates 8 and 9 is a split or two part pinion or sector 10 and 11, said pinion or pinions are of less diameter than the external openings in said transverse 95 chamber, are insertible through it and serve to space said plates at a proper distance apart to cause their flanges to rest slidingly or rotatably against the lateral faces of the walls of said transverse chamber. Both pinion members engage with worm 4, and primarily, both are free to rotate in unison on shaft 7 and also between plates 8 and 9. Just outside of plate 9 is located a substantial washer 12 having therein a square hole 100 which fits a space on shaft 7 which has been squared to receive it, a further extension of shaft 7 is diametrically reduced, rounded and threaded and is provided with a nut 13, and a washer 14, and encircling said rounded and threaded portion of shaft 7 and between washers 12 and 14 is placed a short

heavy flat coil spring 15, which by being compressed by means of nut 13 serves to bring plates 8 and 9 as well as pinions 10 and 11 together in a manner that affords substantially any degree of rigidity required. An angular rotatable adjustment between members or pinions 10 and 11 is effected by the insertion of a taper nose pin 16 which passes through plate 9, pinion 11 and enters 10 slightly into a hole or opening in pinion 10, said hole having been drilled at a slight angular advance from the hole in pinion 11 when considered in relation to the natural or primary alinement of the teeth on pinions 15 10 and 11. The hole in plate 9 through which pin 16 passes is threaded and as pin 16 is also threaded where it contacts with said plate, it is obvious that screwing pin 16 inward will cause a slight rotary discrepancy 20 in the alinement of the teeth of pinions 10 and 11, which will serve to take up any and all slack that may at any time exist between said teeth and the threads of worm 4. The pin hole stated in pinion 10 25 is drilled entirely through said pinion and on the opposite side of said pinion on the same radial line are drilled a reasonable number of additional holes as indicated in Fig. 3, these last stated holes however are 30 drilled but part way through said pinion. On a circumferential line with said holes, a hole is drilled in plate 8, said hole being counter bored and threaded from the outer side. Into this hole may be inserted what I shall 35 designate as an emergency pin 17. This pin is of such length as will cause it to extend through plate 8 and enter a short distance into any one of the holes in pinion 10 that is presented to it. Therefore if nut 13 be 40 slackened and pin 17 be omitted, plate 9 along with pinions 10 and 11 will be free to rotate to any desired position on shaft 7 and can be so rotated, by merely rotating steering post 3 along with its worm 4. As 45 soon as said plate and pinions have been rotated to approximately the desired position, a partial insertion of and a slight pressure on pin 17 will cause it to register and slightly enter the first one of said holes in 50 pinion 10 which is presented to it. Pin 17 may be screwed in until its head or shoulder jams against plate 8 after which by tightening up nut 13 the thus assembled rocker becomes absolutely rigid. Incidental to the 55 machining of the internal, flat or parallel faces of plates 8 and 9 and pinions 10 and 11, a slight clearance cut is taken commencing at the opening through which shaft 7 enters them and extending outward about 60 two thirds of their diameter or to a point indicated by the heavy shaded circular line in Fig. 7. This results in concentrating the bite or compressional contact between said plates and pinions at a point reasonably near 65 their peripheries. The diameters of said

plates and pinions at their average point of contact will vary to some extent but will at least approximate 3" while the average rocker shaft will hardly exceed 1 $\frac{1}{4}$ " in diameter in this or similar devices of average

70

size. It is therefore a well known and demonstrable fact that a reasonably stiff pull of say 125 lbs. upon a 12" to 14" wrench would be ample to tighten a $\frac{3}{8}$ " nut on such or a similar friction plate arrangement as 75 to cause plates such as 8 and 9 to grip pinions 10 and 11 tight enough to twist shaft 7 in two, if said shaft should meet with sufficient resistance such as is frequently encountered by such a steering arm as is indicated by 18, even if the application of the emergency pin 17 be omitted. It is therefore my contention that if emergency pin 17 be omitted and nut 13 be only tightened sufficiently to grip pinions 10 and 11 or 10^a 80 tight enough to meet ordinary steering requirements said pinion or pinions may still be permitted to yield slightly under severe shocks against steering arm 18 without injury to the steering mechanism, and without causing the driver to lose control of the vehicle. If, however, the driver wishes to do so, he would at all times, be at liberty to not only insert the emergency pin, but also irrespective of it to draw nut 13 up 85 tight enough to overcome spring 15 and thereby make the entire rocker substantially rigid as if all parts thereof were integral.

In Figs. 6 and 7 I have presented a modification of the rocking member of my device, Fig. 6 being a plan view chiefly in section and taken through the rocker only, on a line indicated by A. A. in Fig. 1. Fig. 7 is a plan or internal face view of the outer circular plate 9 of said rocker. In the modification, however, shaft 7, plate 8 and the emergency pin are substantially the same as those shown in Figs. 1 to 15 inclusive, a single pinion 10^a simply takes the place of pinions 10 and 11. It is drilled on the side facing the crank arm extension of shaft 7 in the same manner as pinion 10 and is subject to the same method of rotation and emergency pin securement. Circular plate 9, however, is drilled partly 105 through to match the round portion of shaft 7 while the remaining portion has said hole slightly reduced and squared to fit the squared portion of said shaft that lays within its confines, consequently plate 9 is not 110 rotatable on shaft 7, and does not need to be as it does not include or require the use of the adjustment pin 16 shown in Fig. 2. A saucer shaped and properly tempered elastic steel plate 15^a is located between plate 9 and nut 13 instead of the coil spring shown in Figs. 2, 4 and 5 although if desired shaft 7 may be further extended and said coil spring substituted. Ordinarily pinion 10^a is 115 locked against or secured to plates 8 and 9 120

125

130

- by compression which is produced by means of tightening up nut 13, but if desired it may be further secured by the insertion and use of the emergency pin 17. In either type 5 of rocker, however, the user, if he sees fit can tighten nut 13 sufficiently to close spring 15^a as well as coil spring 15 down tight, and thus cause them to act as solid rings or washers, or the springs may be entirely removed.
- 10 if desired, thus rendering either type of rocker extremely rigid. Steering post 3 is insertible through the upper opening in housing 1, and in Figs. 1 to 5 inclusive may be inserted either before or after the rocker 15 is inserted, but when the rocker shown in the modification Fig. 6 is used, the adoption of a single instead of a split pinion renders it necessary for the steering post to be inserted after the rocker has been inserted.
- 20 Either rocker is adaptable to the same housing and in each, the circular, external openings into the transverse chamber of said housing, are closed by the circular plates of said rocker.
- 25 The operation of my device is extremely simple, and while I have not deemed it necessary to show or describe that portion of the steering post leading up to and carrying the hand steering wheel, yet it is obvious 30 to any one reasonably skilled in the art, that such additions are necessary and contemplated along with the various reach rods leading to the axles of the vehicle.
- Turning the steering post 3 with its worm 35 4 which engages with the two part pinions 10 and 11 or 10^a, causes said pinions to rotate correspondingly, and inasmuch as said pinions are locked to plates 8 and 9 and through them to shaft 7 the entire rocker 40 is caused to rock or rotate proportionately in either direction carrying arm 18 with it, thus imparting the desired reciprocating motion to such reach rods and other mechanism as may be employed in order to reach 45 the axles of the vehicle. The device ordinarily is attachable to the vehicle by inserting the external and rounded portion of rock shaft 7 in a hollow sleeve attached to the frame of the vehicle, but when so desired 50 this connection may be supplemented by brackets made integral with or attached to housing 1.
- I am aware that split or two part pinions are extensively used in connection with segments or racks in saw mill head blocks and similar devices for the purpose of eliminating lost motion between said pinions and said racks, but in their application neither of the pinions however, are in a true sense 55 rotatable on their supporting shaft or with a view of bringing them into contact with unworn portions of either the pinions or racks. Usually one of said pinions is rigidly secured to the shaft, while the other is 60 placed alongside of it; and is provided with a limited rotatable adjustment of one or two degrees. I do not therefore seek a broad claim on the use of split pinions for all purposes.
- I do not know, however, of an instance 70 in which split pinions are used in connection with a steering post and worm, or worm alone, or where they are given the functions attached to those shown in my device.
- Figs. 9 and 10 also present a modification 75 of my device, Fig. 9 being an elevation view chiefly in section with portions removed, while Fig. 10 is a transverse view chiefly in section, taken at a point corresponding with A. A. in Fig. 1.
- In Figs. 9 and 10 the distinction consists 80 in slight modification in the housing, pinion and rocker, whereby the rocker is journaled entirely within housing 1, and the bite or contact between the pinion and other 85 rocker members is increased with less compression than is required in Figs. 2 and 6. This effect is produced by constructing pinion 10^b in the form of a ring having tapering internal faces, and of causing plates 8^a 90 and 9^a (which take the place of plates 8 and 9 in Figs. 2 and 6) to contact with said internal bevel faces instead of its side or lateral faces. Plate 8^a is peripherally journaled against the internal circular walls of 95 the transverse chamber, while in order to render all internal parts accessible the large external circular opening into the transverse chamber is closed by a non-rotatable removable circular plate 1^d which fits there- 100 in, is securely fastened to housing 1 by 4 bolts 4^c and at the same time is internally chambered in such manner as to provide a peripheral journal support for plate 9^a of the rocking member. In order to transfer 105 the compressional force of nut 13 to plates 9^a and 8^a and through them to pinion 10^b, a ring or circular plate 12^a is inserted between them which contacts on one side with plate 9^a and on its other side with nut 13, 110 or first against elastic plates 15^a in the event that the latter is used in order to give elasticity to the action of nut 13 upon plates 9^a. A still further modification of my device is illustrated by Fig. 12, which is also a 115 transverse view chiefly in section, taken at a point corresponding with A. A. in Fig. 2. In this modification circular plates 8 and 9 or 8^a and 9^a are dispensed with, and the pinion which is designated by 10^c has a taper bore which contacts direct with rock shaft 7 and which is also tapered to fit said pinion, this slight change calls for a more central form of trunnion than any of the preceding figures, all of which are provided in 120 a reduced diametrical form but similar to those shown in Fig. 10, the removable non-rotatable plate 1^a and bolts 1^c being employed, and the compression force of nut 13 being delivered against pinion 10^c through 125 130

collars or sleeves 12 and 12^a, in substantially the same manner as that employed in Fig. 10, it being optional as to whether the elastic plates 15^a are inserted or not.

5. In each of the modifications shown by Figs. 9, 10, 11 and 12 the taper fit employed between pinions 10^b or 10^c and other portions of the rocker is such as to cause them to release readily when compression is removed.
10. The taper fit in Fig. 10, however, between plate 8^a and rock shaft 7 is such as to cause said members to lock to such extent that plate 8^a must be driven off of shaft 7 in order to disengage and remove it. In each 15 modification, however, the pinions employed are either directly or indirectly locked to rock shaft 7 by compression, and which is preferably produced by means of nut 13, in substantially the manner shown, and which 20 is externally controlled.

What I claim is:—

1. The combination of a housing having a longitudinal and a circular transverse chamber therein, a rotatable steering post entering said longitudinal chamber having a worm thereon, a rocker journaled in said transverse chamber carrying a circular plate which pivotally engages peripherally with the circular walls of said transverse chamber, a pinion on said rocker which engages with said worm; and means for locking said pinion rigidly to said rocker.
2. The combination of a housing having a longitudinal and a circular transverse chamber therein, a rotatable steering post entering said longitudinal chamber having a worm thereon, a rocker journaled in said transverse chamber carrying a circular plate which engages peripherally with the circular walls of said chamber, a longitudinal extension on said rocker carrying a thread and nut, a pinion mounted on said rocker between said circular plate and said nut, said pinion being rigidly locked to said rocker 45 by screwing said nut toward said plate, and teeth on said pinion which engage with said worm.
3. The combination of a housing having a longitudinal and a transverse chamber therein, a rotatable steering post entering said longitudinal chamber having a thread thereon, a rocker journaled in said transverse chamber comprising a circular plate, a pinion carried by said rocker which engages with said worm, and means for locking said pinion rigidly to said circular plate.
4. The combination of a housing having a longitudinal chamber therein and also having a transverse chamber having an external 60 opening therein, a rotatable steering post entering said longitudinal chamber having a worm thereon, a rocker journaled in said housing carrying an externally exposed circular plate which closes said external opening in said transverse chamber, and a pin-

ion also carried by said rocker; which engages with said worm, said pinion being of less diameter than the journal bearing of said rocker.

5. The combination of a housing having a longitudinal chamber therein, and also having a transverse chamber having a lateral circular opening therein; a rotatable steering post entering said longitudinal chamber having a worm thereon, a rocker journaled in said transverse chamber comprising a pair of circular plates which pivotally engage with and close said circular openings, and a pinion confined between said plates which engages with said worm.

6. The combination of a housing having a longitudinal and a transverse chamber therein, a rotatable steering post entering said longitudinal chamber having a worm thereon, a rocker inserted in said transverse chamber carrying a pinion which engages with said worm, and means for pivotally supporting said rocker upon the circular walls of said transverse chamber which lie diametrically outside of said pinion.

7. The combination of a housing having a longitudinal and a transverse chamber therein, a rotatable steering post entering said longitudinal chamber having a worm thereon, a rocker journaled in said transverse chamber comprising a peripherally journaled circular plate, a pinion which engages with said worm, an elastic member, and a threaded member fitted with a nut, said elastic member being externally located between said nut and said pinion.

8. The combination of a housing having a longitudinal and a transverse chamber therein, a rotatable steering post entering said longitudinal chamber having a worm thereon, a rocker journaled in said transverse chamber comprising a circular plate, a pinion which engages with said worm, a means for locking said pinion to said plate by compression, and additional means for further securing said pinion to said plate.

9. The combination of a housing having a longitudinal and a transverse chamber therein, a rotatable steering post entering said longitudinal chamber having a worm thereon, a rocker journaled in said transverse chamber carrying a two part pinion, both members of which engage with said worm, are rotatably adjustable in relation to each other, and externally accessible means for making said adjustment.

10. The combination of a housing having a longitudinal and a transverse chamber therein, a rotatable steering post inserted in said longitudinal chamber having a worm thereon, a rocker journaled in said transverse chamber comprising a rocking shaft, and a toothed member, said toothed member having a meshing engagement with said worm and also being releasable separable

and removable from said rocker irrespective of any separation of said housing and rocking shaft.

11. The combination of a housing having 5 a longitudinal and also a transverse chamber therein, a rotatable steering post inserted in said longitudinal chamber having a worm thereon, a rocker inserted in said transverse chamber comprising a shaft having 10 a plate type abutment, and carrying a pinion which is rotatably adjustable on said shaft and in its relation to said abutment, a

means for precisely predetermining and fixing the rotatable relation between said shaft and said abutment through which said pinion is not only rigidly secured to said abutment but by means of which their relation may be both specifically and rigidly maintained continuously if so desired. 15

Copies of this patent may be obtained for five cents each, by addressing the "Commissioner of Patents, Washington, D. C."

It is hereby certified that in Letters Patent No. 1,243,379, granted October 16, 1917, upon the application of William H. Appleman, of Olean, New York, for an improvement in "Devices for Steering Vehicles," an error appears in the printed specification requiring correction as follows: Page 3, strike out all matter beginning with line 75 to and including line 20, page 4; and that the said Letters Patent should be read with this correction therein that the same may conform to the record of the case in the Patent Office.

Signed and sealed this 26th day of February, A. D., 1918.

[SEAL.]

F. W. H. CLAY,

Acting Commissioner of Patents.
